UNITED STATES PATENT OFFICE.

FELIX G. KAPELMAN, OF NEW YORK, N. Y., ASSIGNOR TO SAMUEL WEISGLASS, OF BROOKLYN, NEW YORK.

CORNER-LOCK FOR BEDS.

1,132,274.

Specification of Letters Patent.

Patented Mar. 16, 1915.

Application filed March 25, 1914. Serial No. 827,014.

To all whom it may concern:

Be it known that I, FELIX G. KAPELMAN, a citizen of the United States, residing in New York city, New York, in the county of Bronx and State of New York, have invented certain new and useful Improvements in Corner-Locks for Beds, of which the following is a specification.

My present invention relates to an improvement in corner locks for takedown metal framing and is more especially adapted for use in bed or spring mattress frames.

One of the objects of the present device is simplicity of structure thereby affording economy in manufacture and at the same time to obtain a reliable structure and one which is proof against abuse which such corner locks sustain in use.

In the accompanying drawings, Figure 1 shows a fragmentary plan view of my device, Fig. 2 is a side elevation of the same taken on the line 1—1, Fig. 1 looking in the direction of the arrows, Fig. 3 is another plan view of my device showing modified use as a spring mattress corner lock. Fig. 4 is a side elevation partly in section taken on the line 3—3, Fig. 3 looking in the direction of the arrows. Fig. 5 is a perspective view of the locking lug which forms one of the parts of my invention, Fig. 6 is a perspective view of a supporting bracket, and Fig. 7 is a perspective view of an angle tapering lock plate therefor.

By referring to Figs. 1 and 2, it will be noted that the corner posts 5 and 6 are slotted as at 7, which slots are for the purpose of permitting the introduction into the tube of a hasp like end 8 of the locking lug 9.

By referring to Fig. 6 it will be noted that the supporting bracket 11 is substantially channel shaped and that one arm 10 therefore is slightly curved in order to conform to the corner post 5, against which it rests. It is obvious that if square or any other type of corner post is used the said arm 10 can be shaped to conform thereto in order to afford intimate contact with the surface thereof. The arm 12 is bent at right angles to the wall 13 and forms a means of attachment thereto of supporting a cross bar 14, or other forms of support, by means of rivets or bolts which are passed through the holes 15, 16, which are shown in the side arm 12.

As a means for attaching the supporting

bracket 11 to the corner posts there is arranged in the curved face of the arm 10, a slot 17 of sufficient width and length to permit the introduction therethrough of the prior mentioned hasp end 8 of the locking lug 9, as indicated in Figs. 1, 2, 3 and 4. After the said hasp 8 has been introduced through the opening 17 in the wall 10 and through the slot 7 of the members 5 and 6, the customary tapered pin 18 is introduced into the opening 19 of the locking lug 9 and the pin is driven down until the member 10 is held in rigid engagement with the corner post. Thus the simple unitary structure is formed with the corner post by the supporting bracket 11 which is not intended to be removed once it is placed in position.

The wall 13 of supporting bracket 11 is bent at a slight angle to the arm 10 thereof as is indicated in Fig. 2, at 20 in order to form an opening at the upper end thereof which is slightly larger than at the lower end. This angle conforms to the taper shown on the arm 22 of the angle lock 21, wherein the edge 23 is straight and the edge 24 of the arm 22 is slightly tapered relative to upper limb 25, in order to enable the said member 21 to be wedged into the supporting bracket 11 against the wall 13. The upper limb 25 of the angle lock 21 has two holes *c* and *d* therein which permit of the riveting thereto of an angle side rail 26.

In assembling, the procedure is about as follows: The locking lug 9 is entered into the slot 17 of the member 13 and this is introduced into the slot 7 of the posts 5 and 6 and the wedge 18 is driven through the opening 19 of the hasp 8. This, as before noted, forces the supporting bracket into engagement with the corner post. The cross bar 14 which is riveted to the two members 12 of the supporting brackets 11, thereby forming transverse or longitudinal struts as the case may be, maintains the corner posts a predetermined distance apart. The corner locks 21, which have previously been riveted to the angled side-rails 26, have tapered arms 22 then introduced into the channel against the side wall 13 of the brace plate 11, and are forced down into the tapered seat previously described. This makes a rigid and economical corner lock and maintains the posts in perfect alinement.

By referring to Fig. 1, it will be noted that the end of the strut 14, which is riv-

eted to the wall 12 of the supporting bracket 11, does not quite extend up to the wall 13 of the said member, and thereby leaves a clearance 14^a which contacts with one side of 5 the lug 22 when it is driven into position. Both ends of the hasp 8 are left square so that they are interchangeable or reversible for the various corner posts and are of such dimensions that they also leave a clearance 10 for the entry of the lug 22 of the corner lock 21, and support the same against looseness or rolling movement during use. The tapered seat 13 of the supporting bracket 11 is enough smaller in dimension so that 15 when the tapered arm 22 of the locking lug 21 is entered therein to a seat, there is a clearance *g* left therebetween as indicated in Fig. 2. This clearance provides for wear and permits of a rigid fit between the two 20 said elements at all times under condition of use. Were the lower face of the corner lock 21 permitted to rest upon the edge *f* (Fig. 2) of the supporting bracket 11, this rigid fit could not be maintained.

25 From the foregoing it is seen that my construction permits of the usual takedown of the bed frame for shipment etc., as the side rails are removable at will, as is customary. However, my corner lock may also be used 30 for obtaining an economical corner lock for permanently assembled frames as in Figs. 3 and 4 wherein is shown a modified use of my device as applied to a mattress frame for beds wherein the side bars of the 35 mattress comprise two tubes 28 and 29 which have their respective ends 30 bent upwardly at right angles thereto, forming posts, and are slotted like corner posts 5 and 6, at their upturned ends 30. The procedure for as- 40 sembling is the same as indicated for the construction shown in Fig. 1. The only variation in structure is that the struts 14 of Figs. 1 and 2 are left out entirely so that the non-rolling support for the arm 22 of 45 the corner lock 21 is taken entirely by the square end of the curved face of the lug 8. Should it be desirable, a rectangular piece may be riveted against the wall 12 in order 50 to form an extra support against the spring tension.

For spring mattress frames the top face of the corner lock 21 may be riveted to an angle rail 31 which is suitably drilled with holes *e* and *f* of sufficient number to permit 55 the introduction and stretching of woven wire fabric or springs 32, or other suitable means used in forming the mattress fabric therefor.

While my device as described in the fore- 60 going is intended to be stamped out of sheet metal, with the exception of the lug 9, which is cast metal, it is obvious that the hasp-like portion might be formed integral with the supporting bracket 11 by utilizing the ma- 65 terial displaced to form slot 17, or if my en-

tire device were of cast metal the hasp-like projection 8, might be cast on the supporting bracket, and other obvious modifications might be made without departing from the spirit of my invention.

Having thus described my invention, I 70 claim:

1. In a corner lock for takedown frames, the combination with a post, of a channel-shaped supporting bracket, one wing of said 75 channel being conformed to the surface of said post, the other wing adapted to support a cross rail, a web between said wings, and a tapered seat formed by the junction of said wings with said web.

2. In a corner lock for takedown frames, the combination with a tubular post, of a channel-shaped supporting bracket, one wing of said channel being curved to conform to the surface of said post, the other 85 wing adapted to be attached to a cross rail, a web between said wings, one of said wings being bent at its junction with said web thereby forming a tapered seat between said wings.

3. In a corner lock for takedown frames, the combination of a slotted post, a slotted channel shaped supporting bracket, one wing of said channel being conformed to the surface of said post the other wing adapted to 95 support a cross rail, a web between said wings, a tapered seat formed by the junction of said wings with said web, a tapered locking plate adapted to removably engage in said seat, a hasp lug arranged to pass 100 through the slots in the bracket and post, and to be positioned in the slotted post, and a taper pin driven into said hasp when positioned in said slotted post whereby to rigidly maintain said corner lock on said post. 105

4. A supporting bracket for takedown frame corner locks made of a single piece of sheet metal and comprising two wings connected to a web member and angularly disposed relatively to one another to form a 110 tapered seat.

5. A supporting bracket for takedown frame corner locks made of a single piece of sheet metal and comprising two wings connected to a web member, one of said wings 115 being bent substantially at a right angle to said web and inclining toward the other of said wings to form a tapered seat.

6. A supporting bracket for takedown frame corner locks made of sheet metal and 120 comprising two wings connected to a web member, one of said wings being angularly disposed relative to said web, and rounded to conform to the contour of a tubular post, the other of said wings converging toward 125 said first mentioned wing to form a tapering seat therewith.

7. A corner lock for takedown frames, comprising a supporting bracket having two arms connected to a web member and angu- 130

larly disposed relative to one another to form a tapered seat, and an L shaped rail locking lug having a tapered arm and a straight rail arm, said tapered arm having 5 two parallel sides and two tapering sides, and being arranged to be impinged in said tapered seat with one of its parallel sides disposed adjacent to said web to be thereby properly positioned.

10 8. The combination with a tubular post having a slot, of a supporting bracket hav-

ing a slot, adapted to register with the slot in said post, a locking lug having a hasp adapted to pass through said slots and be disposed inside of said post, and a wedge 15 secured into said hasp inside of the post whereby to lock said supporting bracket to said post.
